UNITED STATES PATENT OFFICE.

JAMES H. LITTELL, OF NEW YORK, N. Y.

DESIGN FOR A CALENDAR.

SPECIFICATION forming part of Design No. 14,159, dated August 7, 1883.

Application filed April 23, 1883. Term of patent 7 years.

To all whom it may concern:

Be it known that I, JAMES H. LITTELL, a citizen of the United States, residing at New York, in the county and State of New York, have invented and produced a new and original Design for Calendars, of which the following is a specification, reference being had to the accompanying drawings, forming part thereof.

Figure 1 of the drawings represents the front 10 of the calendar spread open; and Fig. 2 is a similar view, showing the back of the same.

A denotes the front of the calendar, B the back thereof, and C the intermediate sheets, the whole being held together at their upper 15 end by an eyelet, D. The front and back of the calendar represent a bottle of rectangular configuration, closed at its upper end by a cork and capsule, and the intermediate sheets, C, are similar in outline to the front and back 20 A B, and have upon their lower edges the cal-

endar for each month in the year, above the calendar each sheet being ornamented by some pictorial illustration, and, if desired, blanks E being left for the insertion of advertisements or other descriptive matter. I propose to employ twelve intermediate sheets C—one for each month in the year, as aforesaid—and supplement these by the front and back.

What I claim is—

A design for a calendar, consisting of a front 30 and back with intermediate sheets having upon them proper data for the months of the year, the front and back representing a bottle and the intermediate sheets being similar in outline, substantially as set forth.

JAMES H. LITTELL.
